[57] **CLAIM**

The ornamental design for a combined computer-controlled drafting table, chair and microprocessor base unit for engineering use, as shown and described.

DESCRIPTION

FIG. 1 is a front elevational view of a combined computer-controlled drafting table, chair and microprocessor base unit for engineering use showing my design;

FIG. 2 is a top plan view thereof;

FIG. 3 is a right end elevational view; and

FIG. 4 is a front perspective view wherein the chair has been pivoted to an alternate position.

The undisclosed rear surface is conventional in appearance.

FIG. 3
